UNITED STATES PATENT OFFICE.

CHARLES H. WILLIAMS, JR., OF CHICAGO, ILLINOIS, ASSIGNOR TO CHICAGO RAILWAY EQUIPMENT COMPANY, OF CHICAGO, ILLINOIS, A CORPORATION OF ILLINOIS.

DUPLEX THIRD-POINT SUPPORT FOR BRAKE-BEAMS.

1,114,210.

Specification of Letters Patent.

Patented Oct. 20, 1914.

Application filed March 18, 1914. Serial No. 825,584.

To all whom it may concern:

Be it known that I, CHARLES H. WILLIAMS, Jr., a citizen of the United States, residing at Chicago, Illinois, have invented

5 a certain new and useful Improvement in Duplex Third-Point Supports for Brake-Beams, of which the following is a full, clear, and exact description, such as will enable others skilled in the art to which it
10 appertains to make and use the same, reference being had to the accompanying drawings, forming part of this specification, in which—

Figure 1 is a partial plan view of my improvement. Fig. 2 is a vertical sectional view. Fig. 3 is a vertical sectional view of a modified form. Fig. 4 is a similar view of another modified form.

In a former Patent No. 997,888, granted 20 to me July 11, 1911, is represented what I conceive to be the best way of preventing brake beam from becoming damaged in service and to insure even shoe wear and full brake beam efficiency. Certain railroads, 25 however, have adopted recently a light spring plank as their standard, and these, together with the use of very light hanger bars, offer an unsatisfactory base or support for the fastening of the third point 30 spring at the center of the truck. Furthermore, in certain roads where slack adjusters are used at the center of the truck brake rigging, it is practically impossible to use a single third point supporting spring at the 35 center.

My present invention has been devised to take care of these conditions and in essential parts is similar to a construction shown in the Williamson Patent No. 567,428, 40 dated September 8, 1896, with this difference, however, that I propose to use shoes on the beam which contact with the duplex spring supports in such a way that the beam will ride easily and freely, permitting 45 lateral movement in just the same way as the present centrally located third point support does.

My present improvement provides everything that my former patent disclosed except catching and holding the beam at the 50 deepest part of the truss depth, but it offers double strength, easier beam replacement, etc.

In the drawings 1 indicates the spring plank of the truck to which is secured, at each side of the center of the beam, a duplex 55 support 2.

3 is the compression member of the beam. 4 is the strut and 5 is the tension member. In Figs. 1 and 2, the tension member, at each side of the strut, is provided with a 60 clip 6 carrying a rubbing surface or wearing shoe 7 for coöperating with the upper surface of the duplex supporting spring 2.

By reference to Fig. 1, it will be observed that this shoe affords a bearing disposed at 65 right angles to the major axis of the duplex supporting spring and consequently the beam has freedom of movement without subjecting the tension member to the shearing action of the supporting spring which in 70 time would reduce the strength of said tension member.

In Fig. 3 I have shown a two-part clip 8 embracing both the compression and tension members, the lower member of which 75 two-part clip is provided with two wearing surface-shoes 9 and 10.

In Fig. 4 I have shown a one-piece clip 11 embracing the compression and tension members and having a single contact point 80 12 for engagement with the duplex supporting springs. In all forms of clips suitable fastening devices, in the form of bolts, are employed to hold the contiguous free ends together. 85

I claim:

1. In combination with a truck having inclined duplex third point supporting members arranged on each side of its center, of a brake beam having removable wear surfaces or shoes to coöperate with said inclined supports. 90

2. A truss brake beam having a clip secured to its compression and tension members, one member of said clip having one 95 or more wear surfaces or shoes.

In testimony whereof I hereunto affix my signature in the presence of two witnesses, this thirteenth day of March, 1914.

CHARLES H. WILLIAMS, JR.
